UNITED STATES PATENT OFFICE.

BENJAMIN M. GRIFFITH AND WILLIAM T. McCULLOUGH, OF PITTSBURGH,
PENNSYLVANIA.

DESIGN FOR A FRAME FOR THE OPERATING MECHANISM OF CHURNS.

43,275.

Specification for Design.

Patented Nov. 26, 1912.

Application filed September 18, 1912. Serial No. 721,103. Term of patent 3½ years.

To all whom it may concern:

Be it known that we, BENJAMIN M. GRIFFITH and WILLIAM T. McCULLOUGH, citizens of the United States of America, residing at Pittsburgh, in the county of Allegheny and State of Pennsylvania, have invented a certain new, original, and ornamental Design for a Frame for the Operating Mechanism of Churns, of which the following is the specification, reference being had to the accompanying drawing, forming a part thereof.

The figure is a perspective view of the frame for the operating mechanism of a churn, illustrating our new design.

We claim:—

The ornamental design for a frame for the operating mechanism of a churn, as shown.

BENJAMIN M. GRIFFITH.
WILLIAM T. McCULLOUGH.
